UNITED STATES PATENT OFFICE

JULIUS R. WEMLINGER, OF NEW YORK, N. Y.

SHEET PILING

Application filed November 21, 1930. Serial No. 497,319.

This invention relates to sheet metal piling and more particularly to corrugated sheet metal piling of the type covered by my Patent No. 1,166,563, dated January 4, 1916, and 5 consists in the improvement hereinafter described and illustrated in the drawing, in which;

Fig. 1 is a cross-sectional view of one pile and of the edges of two adjoining piles; 10 Fig. 2 is a front elevation of one of the piles; and

Fig. 3 is a detail sectional view of a modification.

The advantages of this type of piling are 15 fully set forth in my said patent. It comprises interlocking means which enables the piles to be interlocked by lateral movement as distinguished from the longitudinal driving of one pile into engagement with another, 20 already in situ. The interlocking means of the piling, disclosed in my said patent, consists of clips, riveted or otherwise secured near one of the marginal edges of each pile and so shaped as to leave a space between it 25 and the marginal corrugation to receive the edge of the marginal corrugation of the adjoining pile. The riveting on of these clips in the required positions considerably increases the cost of the piling.

30 It is the object of the present invention to eliminate the extra cost of providing and attaching these clips and at the same time, to reduce the weight of the piles.

I obtain these desirable results by forming 35 the clips out of the metal of the piling itself, by punching them up in suitable dies.

The piling illustrated in the drawing is 40 by way of example only, since it is obvious that the invention is equally applicable to other forms of corrugated sheet piling than that shown, in which the corrugations are semi-circular without the intermediate tangents shown in my patent aforesaid.

Referring now to the drawing, 1 are the 45 main or body corrugations of the sheet and 2, 3, the marginal ones. The outside radius of the corrugation 2 is equal to the inside radius of the corrugation 3, so that the edge 50 of one pile fits snugly in the edge of the adjoining pile. As shown, the corrugations 2

and 3 are of lesser radii than the body corrugations 1, the purpose of which is set forth in my said patent, but this construction has no bearing on the present invention. The clips comprise the curved ends 4 of small 55 radius and the shanks 5, joining said ends to the body of the pile.

It sometimes happens that the clips become bent in the handling of the piling and, 60 to prevent this, I may form strengthening ribs 6 on their backs in the operation of punching them out and die-shaping them.

The plates described are useful for other 65 purposes than piling, for example, as a metal base in road construction.

Having thus described my invention, what I claim is:

Corrugated sheet piling having interlocking 70 clips punched out of the corrugation next to one of the marginal corrugations.

Signed at New York in the county of New York and State of New York this 19th day of November A. D. 1930.

JULIUS R. WEMLINGER.
